UNITED STATES PATENT OFFICE.

CLOVIS M. TAYLOR, OF COLUMBUS, OHIO.

DESIGN FOR AN AUTOMOBILE-BODY.

SPECIFICATION forming part of Design No. 36,008, dated August 12, 1902.

Application filed June 23, 1902. Serial No. 112,937. Term of patent 14 years.

To all whom it may concern:

Be it known that I, CLOVIS M. TAYLOR, a citizen of the United States, residing at Columbus, in the county of Franklin and State of Ohio, have invented and produced a new and original ornamental Design for Automobile-Bodies, of which the following is a specification, reference being had to the accompanying drawings, forming part thereof.

Of the drawings, Figure 1 is a side elevation of my newly-designed automobile-body, and Fig. 2 is a front end view.

As shown in the drawings, the leading or material features of my design consist of the elongated body 1, formed with a transverse channel 2 near or in front of the center of the length of said body. The portion immediately in rear of the channel 2 is raised above the body or provided with an elevation 4, which elevated portion is in the nature of a

panel separated from the rearwardly-extending and lower portion 5 by a bead 6, which curving rearwardly meets the lower or base bead 7 of the body near the rear end of the rearward extension 5. The forward portion 3 of the body in front of the channel 2 is surmounted by a rod or rail 8.

Having described my invention, what I claim as new, and desire to secure by Letters Patent, is—

The ornamental design for an automobile-body as herein shown and described.

In testimony whereof I have signed my name to this specification in the presence of two subscribing witnesses.

CLOVIS M. TAYLOR.
